(57) **CLAIM**

The ornamental design for a chair cover accessory, as shown and described.

DESCRIPTION

FIG. 1 is a perspective view of a chair cover accessory showing my new design;

FIG. 2 is a front elevational view thereof;

FIG. 3 is a back elevational view thereof;

FIG. 4 is a right side elevational view thereof;

FIG. 5 is a left side elevational view thereof;

FIG. 6 is a top plan view thereof;

FIG. 7 is a bottom plan view thereof; and,

FIG. 8 is a perspective view thereof, shown in a position of use with environment.

The broken lines in FIG. 8 are for the purpose of illustrating environment only, and form no part of the claimed design.

1 Claim, 6 Drawing Sheets
